ROTARY OIL BURNERS

John J. McGillis and Hugh D. McGillis, Brockton, Mass.

Application June 29, 1956, Serial No. 594,747

4 Claims. (Cl. 158—77)

This invention relates to improvements in rotary type oil burners. It relates more particularly to improvements in rotary oil burners of the general variety disclosed in our Patent No. 2,738,837, granted March 20, 1956, wherein vaporization of oil is accomplished in a chamber within the burner head from which air is excluded, the vaporized oil, undiluted by air, delivering annularly from the head into intersecting air streams which effect further atomization of the oil and supply oxygen for combustion of the oil. Reference also is made to our copending applications Serial No. 433,486, filed June 1, 1954, which has matured into Patent No. 2,815,806, dated Dec. 10, 1957, Serial No. 483,970, filed Jan. 25, 1955, which has been abandoned, and Serial No. 577,731, filed April 12, 1956, which has matured into Patent No. 2,836,231, dated May 27, 1958, wherein certain improvements upon the invention of our said Patent No. 2,738,837 are disclosed and claimed. The present invention improves upon our said patented disclosure and the disclosures of our said copending applications by providing for more efficient utilization and control and mixing of cold and warm air to attain improved combustion efficiency without need for the careful and critically precise regulation and control of the incoming cold air which heretofore has been required.

Oil burners of the general type to which the invention relates customarily have a rotary head comprising a pair of opposed dished plates or disks fixed in spaced relation on the upper end of a vertically disposed hollow shaft through which oil delivers between the plates or disks. The oil is vaporized and atomized between the plates and discharged centrifugally around the periphery of the rotating burner-head. In our said prior patent and copending applications, the vaporization and atomization of oil which takes place between the dished plates or disks is accomplished without any air being admitted to the space between the plates or disks, and the discharging oil is substantially undiluted by air, and the air for combustion is supplied by intersecting streams of air at the combustion region which streams of air also further atomize the oil.

It is among the objects of our present invention to provide a rotary oil burner head from which atomized and/or vaporized oil, undiluted by air, is discharged in a stream annularly around the head, and upper and lower annular streams of air are discharged outwardly and downwardly and outwardly and upwardly, respectively, to intersect each other and the stream of oil at two annular, radially different locations, the said lower air stream being a mixture of fresh air and hot combustion products drawn from the combustion region beside the burner head, and the said upper air stream being a mixture of fresh air and hot air and combustion products drawn from the region of the combustion chamber which is above the burner head.

Another object of this invention is to provide a rotary oil burner head from which a stream of atomized and/or vaporized oil and upper and lower streams of air inter-

sect each other annularly around the burner head, said upper stream of air consisting of fresh air delivered upwardly through tubular portions of the head and moving thence annularly outward between elements of the head, 5 the said outwardly moving air drawing into the annular stream hot air and hot products of combustion from the region above the burner in the combustion chamber, whereby said upper stream of air delivers annularly from said head in condition to promote efficient combustion 10 of said stream of oil.

A further object of this invention is to provide a rotary oil burner wherein a sleeve is adjustable for regulating the flow of fresh air to the burner head, and the fresh air passage through said sleeve is surrounded by a substantial quantity of heat insulating material for minimizing conductance of heat in one general direction away from said head.

It is, moreover, our purpose and object generally to improve the structure and operative efficiency of rotary oil burners, and more especially rotary oil burners wherein oil undiluted by air delivers from the head in atomized and/or vaporized condition; and air for combustion delivers from the head in streams which intersect each other and the stream of delivering oil at an annular region of 25 combustion of the oil.

In the accompanying drawings:

Fig. 1 is a cross-sectional view, with some parts in elevation, of a rotary oil burner embodying features of our present invention;

30 Fig. 2 is a cross-sectional plan view, on line 2—2 of Fig. 1;

Fig. 3 is a bottom plan view with the burner shaft in cross-section on line 3—3 of Fig. 1; and

Fig. 4 is a fragmentary top plan view of our improved 35 oil burner.

Referring to the drawings, a rotary oil burner head, indicated generally at 10, may be supported in a conventional manner by legs or posts 12 which also may support an electric motor 14 with means (not shown) for 40 adjustment of the motor vertically in general parallelism with the legs. Usually, the legs 12 also include provision for adjustment of their lengths to facilitate proper positioning of the head 10 with its axis vertical even though a floor or other support may be uneven.

45 A generally horizontally disposed platform 16 is fixed on the upper ends of legs 12 and has a relatively large central opening 18 within which an annular sleeve 20 is vertically adjustable by means of an adjusting screw 22. The screw 22 is rotatably fixed on platform 16 with its

50 threaded shank extending through and engaging threads in projecting ear 24 on sleeve 20. An upstanding flange portion 26 on platform 16 closely surrounds sleeve 20 for guiding the sleeve and restraining it against vibration in each of its positions of vertical adjustment. Flange 55 portion 26 has an annular enlargement 28 which is hollow at 30 for accommodating the screw 22 and ear 24.

Refractory elements 32 of a heater ordinarily rest on platform 16 outward of and all around the annular enlargement 28 of flange portion 26.

60 Motor 14 has a vertically disposed shaft 34 of conventional hollow form, and oil from any suitable source is conducted upwardly through the shaft to the burner head 10 which is shown fixed on an extension of the shaft 34 for rotation with the shaft when motor 14 is running.

65 As represented in Fig. 1, the hollow motor shaft 34 has its upper end connected to a hollow extension 38 on the upper end of which are rigidly secured the elements of the rotary burner head 10. Extension 38 has the cylindrical enlargement 40 thereon, and has one threaded portion 44, of reduced diameter, at the upper end of extension 38.

Two dished annular plates 46, 48 are clamped rigidly

to extension 38 with their dished or concave sides toward each other and with their peripheral lips spaced slightly apart. Upper plate 46 has a central hole for receiving the upper threaded end portion 44 of extension 38 and is clamped against the shoulder at the upper side of enlargement 40 by means of nut 50, with a third dished plate 52 and spacing collar 54 intervening between the plate 46 and nut 50.

The dished plate 48 which is below plate 46 has a central opening whereby it may be arranged on extension 38 of the motor shaft before the lower end of the extension is connected at 36 to the motor shaft; and this plate 48 may be slid along extension 38 into engagement with the shoulder at the lower end of enlargement 40 and clamped against the shoulder when nut 56 is tightened on the threaded portion 42 of the extension 38.

Before clamping the plates 46, 48 to extension 38, by tightening of nuts 50, 56, a series of short rigid tubes 58 are loosely assembled in spaced positions to extend generally in vertical directions across the space between the plates 46, 48. The opposite ends of the tubes may be exteriorly tapered for entering plate holes 60 which are slightly smaller in diameter than the exterior diameter of the tubes. Hence, when plates 46, 48 are clamped to extension 38, by tightening nuts 50, 56, the tapered tube ends become gripped by the walls of plate holes 60 and the tubes effectively plug the holes against passage of air between the exterior surfaces of the tubes and the walls of plate holes 60. But, the tubes 58 provide substantial air passages extending vertically across the space between the dished plates 46, 48 with none of this air having access to the space between the plates 46, 48.

The hollow or bore of extension 38 extends into and terminates within the enlargement 40, as at 41, and a series of relatively small diameter passages 62 extend radially outward through the enlargement 40 from the terminal portion 41 of the bore. Oil conducted upward through motor shaft 34 and its extension 38 delivers through the radial passages 62 into the space between dished plates 46, 48. Preferably, the hollow motor shaft 34 and/or the hollow extension 38, or any desired portions thereof, will be provided with means, such as the interior threads 39 in extension 38, for inducing or aiding the upward travel of oil and especially the heavier and more viscous oils, such as No. 6 fuel oil, for example.

Inasmuch as the plates 46, 48 are rigid on the relatively high speed rotating burner head, oil delivering into the space between plates 46, 48 is carried outward on and between the plates by centrifugal force, with substantial vaporization and/or atomization of the oil being accomplished between the plates 46, 48 while air is excluded from the space between the plates. Hence, vaporized and/or atomized oil substantially undiluted by air discharges from the slightly spaced peripheral lips of the plates approximately in a horizontal plane with a further atomizing effect resulting from the centrifugal discharge of the oil into space annularly around the rotating head.

Fan blades 64, 66 are provided on exterior peripheral portions of the dished plates 46, 48, respectively, they being shown secured, respectively at 65, 67, with the blades relatively close to the inclined margins of the plates.

The previously mentioned third dished plate 52, above the dished plate 46, has diameter substantially larger than plates 46, 48 and has its outer marginal portion inclined outwardly and downwardly at 53. The fan blades 64 are located between plates 46 and 52.

A fourth dished plate 68 is mounted on the burner head below dished plate 48 and it has a diameter substantially the same as plate 52, with its outer marginal portion inclined outwardly and upwardly at 69. As shown, plate 68 has a central opening through which the exteriorly threaded portion 42 of extension 38 loosely extends, with a spacing collar 70 loose on the extension and intervening between plates 48 and 68 and with nut 56 in position

to clamp plates 48, 68 and collar 70 together and against the under shoulder of the enlargement 40 of extension 38. Plate 68 has one annular series of holes 72 therein, each hole being generally opposite one of the vertical tubes 58. Another annular series of smaller holes 74 in plate 68 are outward from the holes 72.

The structure thus far described is generally similar to the comparable structure disclosed in our said co-pending application Serial No. 577,731.

Our present invention provides a smoother and more concentrated flow of incoming cool air to the burner head and minimizes conduction of heat from the extremely hot region of the head downward to the motor 14. More important, however, is the introduction of means in the burner head whereby relatively hot air and products of combustion which normally accumulate above the burner in the combustion chamber are drawn into the stream of air which is moving outwardly between the two upper plates 46 and 52. Heretofore, this accumulation above a burner of hot air and hot products of combustion has presented a problem in that the burner head would become objectionably heated thereby. In some cases it has been found necessary, or desirable, to insulate the upper surface portions of the burner head from the extremely hot gaseous products accumulated above the burner.

According to our present invention, the upper plate 52 is provided with an annular series of holes 76 disposed outwardly of the circle of the short tubes 58. Hence, the outwardly moving stream of air, supplied by the air passing upwardly through the tubes 58, draws hot air and hot gaseous products of combustion from above the burner into the stream through the holes 76. The region above the burner is thereby relieved, and the air and gaseous products in the stream which issues outwardly and downwardly from between the plates 46, 52 is in an improved condition for contributing to atomization and/or vaporization of oil and effective combustion of the oil. Hot products of combustion from regions surrounding the burner head are drawn, primarily through the holes 74 in lower plate 68, into the lower stream which delivers outwardly and upwardly from between the plates 48 and 68, generally the same as in our said co-pending application Serial No. 577,731.

The adjustable sleeve 20, below the burner head, has a frusto-conical member 78 mounted therein with its smaller end open and disposed under the portion of plate 68 which intervenes between the two circular series of holes 72, 74 and moves toward or from plate 68 when sleeve 20 is adjusted by means of screw 22. Hence, a large part of the upwardly delivering relatively cool air passes upwardly through the inner circle of holes 72 in plate 68 and through the tubes 58. A cover 80 closes the upper end of sleeve 20 around member 78, and, preferably, a substantial mass of asbestos 82, or other heat-insulating material, fills the space within sleeve 20 which surrounds member 78 below the cover 80. The asbestos serves to minimize conductance of heat from the burner head downwardly to the motor 14.

When the burner head rotates at relatively high speed, the fan blades 64, 66 induce air circulation by drawing cold or relatively cold air into the lower end of sleeve 20 through the manually operable shutter-type valve means 84. Shutter elements 85 of the valve means are manually operable by handle 86 for selectively increasing the size of the air inlet passage through the valve means. The fan blades also induce flow to the burner head of warm or hot air and products of combustion from the combustion chamber of the heater with which the burner is associated. Some of this relatively high temperature air and gas is drawn inward between lower plate 68 and the cover element 80 on sleeve 20. Inasmuch as the series of holes 74 in plate 68 are outward of the upper end of frusto-conical member 78 a relatively large amount of the inwardly moving warm air is drawn through holes 74 under the influence of the lower fan blades 66. How-

ever, an appreciable amount of the inwardly moving warm air is drawn inward past member 78 and into the cold air which is being drawn upwardly through the plate holes 72 and tubes 58 under the influence of the upper fan blades 64. Also, some of the cold air may be drawn outwardly over the upper end of member 78 and into plate holes 74, and some of the predominantly cold air passing upward through plate holes 72 is drawn outwardly between plates 48, 68 and into the predominantly warm air passing upwardly through plate holes 74. Hence, a mixture of cold and warm air is drawn outwardly between plates 48, 68 by the lower fan blades 66, and this air is propelled outwardly and upwardly across the horizontal plane of discharge of oil from the burner head.

The major portion of the predominantly cold air passing upward through plate holes 72 passes through the tubes 58 to the space between plates 46, 52 with cooling effect on the burner head. Under the influence of the upper fan blades 64, this air from tubes 58 is drawn outwardly between plates 46, 52, being heated somewhat by contact with hot parts of the burner head. However, hot air and hot products of combustion are drawn through holes 76 into this outwardly moving stream prior to propulsion thereof outwardly and downwardly across the horizontal plane of discharge of oil from the burner head.

It will be noted that the plates 52, 68 are substantially larger in diameter than the plates 46, 48, and that the inclined margins of the larger plates are located and adapted to direct propelled air in streams which intersect each other outside the peripheries of the plates. Other substantial volumes of the propelled air, in the near vicinity of the fan blades, are driven more directly in streams which intersect each other appreciably inward from the region of intersection of the first mentioned air streams. However, both regions of intersection of air streams are in the general plane of horizontal discharge of oil from the burner head and the atomized and/or vaporized oil, substantially undiluted by air, is subjected to the action of the intersecting streams of air at the inner region of intersection, represented by the arrows at A, and the air in the streams which intersect at the arrows B will have atomized and/or vaporized oil mingled therewith in condition to be further atomized and thoroughly mixed with air at the region B. The regions of intersection at A and B extend annularly all around the burner head, and any suitable ignition means 88 may be provided, adjacent the region B, for igniting the fuel mixture.

The treatment of the discharging oil, by subjecting it to the action of intersecting streams of air in succession at radially different locations substantially improves the combustion efficiency as described in our said co-pending application Serial No. 577,731. We have discovered, however, that the needed careful and minute adjustment of sleeve 20, which is essential to attainment of a stable flame having maximum combustion efficiency in the burner of our said co-pending application Ser. No. 577,731, is, to a great extent avoided by the herein disclosed induction of hot air and hot gasses into the upper stream from the region above the burner. Actually the sleeve 20 may be set anywhere within a considerable range of positions without appreciably affecting the stability and high combustion efficiency of the flame produced by our presently disclosed oil burner.

It is intended that the patent shall cover, by suitable expression in the appended claims, whatever features of patentable novelty exist in the invention disclosed.

We claim as our invention:

1. A rotary oil burner for operating within a combustion chamber, comprising a first pair of dished plate elements secured together in spaced relation with their dished sides toward each other to provide an atomizer chamber between them, a second pair of dished plate

elements fixed relative to said first mentioned pair, one plate element of said second pair being spaced above and the other spaced below said first mentioned pair of plate elements, and all of said plate elements being concentric on a common vertical axis for rotation as a unit on said axis, means for delivering oil into the said atomizer chamber, said oil moving outwardly in response to rapid rotation of said plate unit and discharging annularly and centrifugally as a stream of atomized oil from between said first pair of plate elements, means defining flow passages connecting the space between the lower plate elements of said first and second pairs of plate elements with the space between the upper plate elements of said first and second pairs of plate elements, means defining a plurality of radially inner openings and a plurality of radially outer openings through the lower one of said second pair of plate elements, means rotatable in unison with said first pair of plate elements for inducing flow of relatively fresh air through said radially inner openings and thence in substantial part through said connecting passages to and outward within said space between the upper plate elements of said first and second pairs of plate elements for constituting an upper outwardly flowing air stream, another part of said induced fresh air being induced outwardly within the space between the lower plate elements of said first and second pairs of plate elements for constituting a lower outwardly flowing air stream, said flow-inducing means and said lower air stream acting to draw heated air through said radially outer openings into said lower air stream, means providing an annular series of openings through the upper plate element of said second pair of plate elements for entrance of heated air from above the burner into said upper air stream, the lower and upper plate elements of said second pair of plate elements having annular marginal portions inclined respectively upwardly and outwardly and downwardly and outwardly for directing said streams of air in directions to intersect each other and said stream of oil discharging from between said first pair of plate elements.

2. A rotary oil burner as in claim 1 wherein said flow inducing means are fan blades disposed annularly on and around the exterior peripheral margins of each plate of said first pair of plates, and wherein there is a frustoconical means below the lower plate which is manually adjustable toward and from said lower plate, said frustoconical means providing an inflow passage for said induced fresh air, and a substantial mass of heat-insulating material surrounding said frusto-conical means and movable therewith for minimizing conductance of heat downwardly from the said plates of the burner.

3. A rotary oil burner for operating within a combustion chamber, comprising four generally circular plates relatively fixed for rotation in unison in a combustion chamber on a common vertical axis, two adjacent ones of said plates being spaced apart for forming an annular atomizer chamber between them, and the other two plates being spaced, one above and one below the two which form the said chamber whereby a lower flow space and an upper flow space are provided respectively below and above the said chamber, means for delivering oil into said atomizer chamber, said oil moving outwardly between the two said chamber-forming plates, in response to rapid rotation thereof, and discharging centrifugally from between them as an annular stream of atomized oil, means defining flow passages for entrance of fresh air into said lower and upper flow spaces, fan means for inducing flow of fresh air into and through said flow spaces thereby to provide lower and upper outwardly flowing air streams, means defining an annular series of openings through the lowermost and the uppermost plates radially outward from said flow passages, said fan means and said lower and upper air streams inducing entrance of heated air through said openings and into said outwardly flowing lower and upper air streams, peripheral

marginal portions of the lowermost and uppermost plates being inclined respectively upwardly and outwardly and downwardly and outwardly to direct said lower and upper air streams in directions to intersect each other and said annular stream of oil discharging from between said chamber-forming plates, and means for controlling the volume of said induced fresh air in said lower and upper air streams at the region of their said intersection.

4. A rotary oil burner as in claim 3 wherein vertically adjustable means provides a tapering air-inflow passage having its smaller end open adjacent to a central portion of said lowermost plate, said air volume controlling means being at the larger end of said inflow passage, said flow passages comprising a radially inner annular series of openings through said lowermost plate opposite said open smaller end of said tapering inflow passage, and an annular series of relatively short tubes extending across said atomizer chamber from said lower flow space to said upper flow space with the lower ends of said tubes generally opposite said radially inner openings in the

lowermost plate, the first mentioned annular series of openings through said lowermost plate being radially outward of said open smaller end of said tapering inflow passage.
